UNITED STATES PATENT OFFICE

2,507,232

BOILER

William B. Van Wert, Peckville, Pa.

Application June 24, 1947, Serial No. 756,684

2 Claims. (Cl. 122—368)

1

This invention relates to boilers which are adapted for use in the heating of water for household heating systems, but is especially adapted for steam or vapor heating systems.

An object of the invention is to provide a boiler of simple construction that may be produced inexpensively and having a large amount of heating surface in relation to water capacity, permits direct contact with the combustion chamber thereof, providing for quicker heating of the water.

Another object of the invention is to provide a boiler having a construction of such character that it operates with a high degree of efficiency at a low fuel consumption.

A further object of the invention is to provide a boiler having a primary and secondary water chamber or jacket and wherein return condensation from the steam or vapor heating system returns to the secondary water chamber or jacket to be heated by flue gasses before passing into and mixing with the water in the primary water chamber or jacket, thus preventing the shock or dampening effect so common in present day steam or vapor heating systems.

With the above and other objects and advantages in view, the invention consists of the novel details of construction, arrangement and combination of parts more fully hereinafter described, claimed and illustrated in the accompanying drawing in which:

Figure 1 is a top plan view of an embodiment of the invention;

Figure 2 is a vertical sectional view on the line 2—2 of Figure 1;

Figure 3 is a transverse sectional view on the line 3—3 of Figure 2 and

Figure 4 is a transverse sectional view on the line 4—4 of Figure 2.

Referring more in detail to the drawing, the boiler 10 embodying the invention has side walls 11 and 12 respectively, a front wall 13 and a rear wall 14, which are welded together along their vertical edges to form the boiler 10. A top 15, having a centrally located inlet 16, is then welded to the upper edges of the walls.

Secured to the inner surface of the rear wall is an inner construction which is similar to the boiler 10, having side walls 17 and 18, a front wall 19, a top 20 and an inset rear wall 21. The boxlike structure 22 thus formed provides the combustion chamber 23. The lower edges of the walls of the structure 22 are provided with outwardly right angularly extending flanges 24 and the sidewalls, top and front wall form the water

2

chamber or jacket 25, while the rear wall forms the water chamber or jacket 26.

The rear wall has a flue 27 welded at right angles thereto which communicates with the combustion chamber 23 and extends outwardly of the wall 14 through the opening 28 which is sealed by welding the flue thereto. The front wall also has a flue 29 welded at right angles thereto which communicates with the combustion chamber 23, and extends outwardly of the wall 13 through the opening 30 which is sealed by welding the flue thereto.

The top 20 of the enclosure 22 is provided with short tubes 31 extending upwardly therefrom, which communicate with the chamber 26, and the side walls 17 and 18 are provided with three relatively spaced rectangular horizontally inclined water tubes 32 which are welded at their open ends to the side walls 17 and 18, and the tubes communicate with the chamber 25. The tubes 32 are within the combustion chamber 23 and the center tube is supported by a plate 33 welded thereto, and to the inner surface of the top 20.

25 A substantially U-shaped water tube 34 is welded to the side walls 17 and 18 about the tubes 32, and the tube 34 has a short leg 35, a base 36 and a long leg 37 which extends downwardly to the lower end of the side walls 17 and 18.

30 The base 36 underlies the tubes 32 and a boxlike structure 38 extends from the side wall 11 to the side wall 17 and is provided with a clean out door 39, while a boxlike structure 40 extends from the side wall 12 to the side wall 18, and is provided with a clean out door 41.

35 The boiler sets on a frame 42 which is provided with an annular upstanding flange 43 to retain the boiler thereon, and a stoker 44 passes through the frame 42 to provide heating means for the boiler.

40 A portion 45 is provided in the frame 42, transversely thereof, in alignment with the leg 37 of the tube 34, and the frame, at this side, is provided with a clean out door 46.

45 The water line in chamber 26 is level with the upper ends of the tubes 31 and this line is constant, maintained by return condensation to chamber 26 from the heating system. The water line in chamber 25 is maintained by means of the manually operated valve 47 or an automatic feeder to compensate for any losses of the water in the chamber 26, through the vent valves in the heating system. The returning condensation from the steam or vapor heating system returning to the chamber 26 through the pipe line 49,

is heated by the flue gasses passing outwardly of the flue 27 before it passes through the tubes 31 to mix with the water in the chamber 25. Thus shock or dampening effect of cool water returning to the chamber 25, which is common in present day steam or vapor heating systems, is prevented. A visible water gauge 48 communicating with the top of the chamber 25 of the boiler 10 gives a visual check of the water level in the chamber 25. In this manner, the water in the chamber 25 can be replenished as necessary through the valve 47 which permits the water to enter chamber 26 first, and then overflow into the chamber 25 through the pipes 31 until the proper water level is reached.

The boiler is made in sheets which are welded together along their vertical edges; the tubes are welded to the inner enclosure and the inner enclosure is then welded to the boiler. The flues are then welded as previously described, and the boiler is ready for connection to a water supply.

There has thus been provided a boiler construction made of sheet metal plates welded at their abutting edges. The heat for the boiler contacts a wide area of the interior construction of the boiler, which houses the water to be heated, and the boiler is particularly advantageous in use in heating systems utilizing steam or vapor in transmitting heating energy.

It is believed that the simplicity of the construction of the boiler will be apparent to those skilled in the art, and it is to be understood that changes in the minor details of construction, arrangement and combination of parts may be resorted to, provided they fall within the spirit of the invention and the scope of the appended claims.

Having thus described the invention, what is claimed as new and desired to be secured by Letters Patent is:

1. A boiler of the character described, comprising sheet metal wall plates secured together along their vertical abutting edges, a top plate secured to the upper edges of said wall plates, a

second set of sheet metal wall plates secured together along their vertical abutting edges and to one of the first mentioned wall plates interiorly thereof to form a combustion chamber and a water jacket or chamber, rectangular horizontally disposed relatively spaced water tubes secured to opposite wall plates of said second set of wall plates, a substantially U-shaped tube secured to the opposite wall plate and enclosing said first tubes, a depending tube formed on the U-shaped tube at one end thereof and extending downwardly to the ends of the side walls all of said tubes communicating with said water jacket or chamber, said tubes forming circuitous passages through which the heat passes for the heating of the water in said tubes and jacket.

2. A boiler of the character described, comprising an outer boxlike structure and an inner boxlike structure, both of said structures being closed at the top, the inner structure being open at the bottom and the outer structure being closed at the bottom by an annular flange formed on said inner structure at the lower ends thereof, rectangular horizontally disposed relatively spaced water tubes and a U-shaped water tube enclosing said first water tubes and having a depending portion formed integral therewith extending transversely of the inner structure and all of said water tubes secured to the walls of said inner structure and a frame for supporting said structures above a fire box.
